UNITED STATES PATENT OFFICE

149,112

DESIGN FOR A SHOE RACK

Albert S. Darby, Big Spring, Tex.

Application July 31, 1946, Serial No. 132,148

Term of patent 3½ years

(Cl. D80—8)

To all whom it may concern:

Be it known that I, Albert S. Darby, a citizen of the United States, residing in Big Spring, in the county of Howard and State of Texas, have invented a new, original, and ornamental Design for a Shoe Rack, of which the following is a specification, reference being had to the accompanying drawing, forming a part thereof.

Figure 1 is a front elevational view of a shoe rack showing my new design;

Figure 2 is an end elevational view of the shoe rack shown in Figure 1; and

Figure 3 is a plan view of one of the shoe supports.

I claim:

The ornamental design for a shoe rack, substantially as shown.

ALBERT S. DARBY.
